CLAIM

The ornamental design for a multicomponent cartridge, as shown and described.

DESCRIPTION

FIG. 1 and FIG. 2 are perspective views of a multicomponent cartridge showing the new design;

FIG. 3 is a top view thereof;

FIG. 4 is a bottom view thereof; and,

FIG. 5, FIG. 6, FIG. 7, and FIG. 8 are side views thereof. The broken lines in the drawing depict portions of the multicomponent cartridge that form no part of the claimed design.
